SYSTEM FOR CONTINUOUS OPERATION OF SERIES CONNECTED HERMETICALLY CLOSED CENTRIFUGAL SEPARATORS

Fredrik Teodor Emanuel Palmqvist, Solna, and Walter Hoffmann, Lidingo, Sweden, assignors to Aktiebolaget Separator, Stockholm, Sweden, a corporation of Sweden

Filed Apr. 22, 1957, Ser. No. 654,213

Claims priority, application Sweden Apr. 26, 1956

12 Claims. (Cl. 233—18)

The present invention relates to a system for continuous operation of at least two hermetically closed centrifugal separators which work in series and are controlled independently of each other.

A system of the kind stated above may be used in various industries for continuous manufacture of a product, where a component must be separated from one or more other components in separate steps. This is the case, for instance, when refining fatty oils, where the oil first may be degummed, then neutralized with alkali, then decolorized with alkali, and washed with water in order to be freed from its content of soap, and finally bleached and deodorized. Each one of the above operations is normally followed by a separating step.

Another similar industrial field is the production of antibiotics, for instance penicillin, where, in order to attain the best possible recovery (maximum yield) of the penicillin, it is necessary to make repeated extractions of the raw material with a suitable agent, for instance amyl acetate. After each extraction step, the extract is separated from the aqueous phase.

A third important industrial field is soapmaking. Here it is necessary to separate the soap from spent lye after graining and from nigre after fitting. Graining as well as fitting may be effected repeatedly in order to attain a high quality of soap.

In the three industrial fields mentioned above as examples, it is desirable to operate in a totally closed system, for reasons which will now be described.

When refining fatty oils, it has been found that an oxidation of the oil impairs its quality. A measure for the degree of oxidation is obtained by determining the peroxide number of the oil and preferably the carbonyl content of the oil, both of which are low in an oil of good quality. Further, it has been found that a fatty oil refined in a totally closed system has a better keeping quality than an oil refined in an open or partly open system, even though the two oils after refining (including bleaching or deodorizing) have the same peroxide number. In refining methods which use an extraction agent for the oil, for instance naphtha or hexane, it is also desirable to avoid losses of the extraction agent because of evaporation.

In the preparation of penicillin, it is of primary importance to prevent evaporation of the extraction agent, particularly as the extraction of the penicillin is carried out in several steps.

In soapmaking, it is desired to avoid contact with the

2

air for at least two reasons, namely, oxidation can darken the soap, and admission of air into the soap mass causes difficulties when it comes to separating the neat soap from the nigre after fitting. Further, the subsequent 5 milling, etc., may under certain circumstances become extremely difficult if the soap contains air. In addition, open systems have the inconvenience that the soap solidifies at open points, for instance in the receiving vats at the outlets of the separator, by being cooled. This presents difficulties in the passage of the soap through the system.

On the other hand, when it is attempted to avoid these inconveniences by making the system totally closed (connecting successive separators through closed lines), then 15 new problems are encountered. That is, in order to allow the closed centrifugal separators to work satisfactorily, the boundary levels adjusted in the separators must not be displaced owing to pressure variations arising in the closed system and propagating through it. These variations must therefore be prevented from asserting themselves from separator to separator in the closed system, so that the various separators can be controlled individually without disturbing each other.

The principal object of the present invention is to provide 25 a system which overcomes the above-noted difficulties.

According to the invention, an outlet of one centrifuge is connected with the inlet of a second centrifuge by a closed line provided with a pumping means of a capacity 30 which is at least equal to the amount of medium maximally discharging per unit of time from the first centrifuge. Also, a controllable throttle member or valve is provided in an outlet from the second centrifuge; and in the closed line between the centrifuges is provided a 35 device for maintaining constant pressure in a part of the line, preferably between the first centrifuge and the pumping means, as calculated in the flow direction. The closed line between the separators includes the device or devices in which the various treatments between the separators are to be carried out. These devices are, of course, of a closed design. The controllable throttling member or valve, may consist of exchangeable throttle discs; but in a continuously operating plant it is, of course, desirable that the throttling member consist of a 45 throttle valve which is controllable during operation and can be manually or automatically operated.

As the pumping means employed must have a capacity which is sufficient for a maximum output in the plant, it may in normal operation be allowed to work only 50 with a capacity below the maximum. If the soap mass or other medium flowing through the system contains a component which can be evaporated relatively easily (for instance water) so that its vapor tends to fill the spaces on the suction side of the pumping means, a positive pump may be used as the pumping means. By this is meant a pump whose capacity is directly proportional to the number of revolutions of the pump, such as a piston pump, sliding vane pump, screw pump, or gear pump. The two latter types of pump are preferred in 55 the system according to the invention. As a positively working pump in normal operation will produce, on its suction side, a vacuum which disturbs the pumping work, especially when the pump medium does not contain any easily evaporated component, a pump of a different type

(for instance, a centrifugal pump) may be employed. It has proved desirable, however, to use a positively working pump owing to its ability to feed the medium practically independently of the counterpressure. In that case, the pump may be designed so that there is a certain allowable leakage between the pumping parts, or it may be provided with a return line joining the pressure side of the pump with the suction side of the pump. This counteracts formation of vacuum on the suction side of the pump.

If the quantity flowing per unit of time through the system has a tendency to vary to a certain extent, a manual control of the throttle member in the outlet of the second centrifuge will not be satisfactory. In that case a conventional type of valve adapted to keep constant pressure may be provided in the outlet of the second centrifuge. Such valve must keep constant pressure at its inlet side, that is, in the centrifugal outlet proper. For the same reason, it may be desirable to insert a similar valve in the above-mentioned outlet of the first centrifuge as well as in any other outlets of the centrifuges.

In the above case, when a positively working pump is provided with a return line, it may be advantageous to insert in the return line a valve (such as a spring-loaded valve) which opens at a determined pressure difference between the pressure side and suction side of the pump. This makes it possible to ensure that the medium is supplied to the second centrifuge at a certain minimum pressure.

When using a positively working pump with a return line, according to an alternative embodiment of the invention, the device for maintaining a constant pressure may consist of a valve provided in the return line and which keeps constant pressure on the suction side of the pump. If, however, the pressure in the inlet line of the second centrifuge in this case should be considerably reduced because of some disturbance in the operation, a valve keeping a constant pressure at its inlet side may be provided in the closed line after the positively working pump and its return line. The pressure drop in the second centrifuge is thereby prevented from disturbing the separation process in the first centrifuge.

When a valve in the return line keeps constant pressure on the suction side of the pump, this means that the pressure in the inlet of the second centrifuge must be considerably higher than the pressure in the outlet of the first centrifuge. For some reasons (e.g. sealing requirements) this is not always suitable. This difficulty may, however, be eliminated by providing a controllable throttle member in the closed line after the first centrifuge but before the connection of the return line. This makes it possible to keep a considerably lower pressure on the suction side of the pump than in the outlet proper from the first centrifuge, so that a lower pressure can also be kept in the inlet of the second centrifuge.

The embodiments described above have proved suitable for use in soapmaking. However, for refining a fatty oil it is desirable to use a modified embodiment due to different conditions of operation. Thus, in this modified embodiment no provision should be made for filling the spaces on the suction side of the pump with steam, and, further, an accurate adjustment of the boundary levels in the centrifuge is required in order to prevent soapstock from being entrained with the separated oil. In this case, it is desirable to maintain a constant supply of oil to the system and a corresponding constant dosage of the various reagents to the oil. As a result, the system should be equipped with a means for keeping a constant supply to the first centrifuge; it being assumed that the pumping means consists of a positively working pump with a return line connecting the pressure side of the pump with the suction side of the pump, and that the means for maintaining a constant pressure consists of a valve provided in the return line and which keeps a constant pressure on the suction side of the pump.

Further, in the closed line after the first centrifuge but before the connection of the return line, there should also be provided in this case a controllable throttle member if, for reasons indicated above, it is not desired to keep a considerably higher pressure in the inlet of the second centrifuge than in the outlet of the first centrifuge.

According to one embodiment of the invention, the means for keeping constant supply to the first centrifuge comprises a positive pump in the inlet line of the first centrifuge, and a throttle valve between this pump and the centrifuge. A closed line, starting from a point of the inlet line between the pump and the throttle valve, connects the pressure side of the pump with the suction side of the pump, and inserted in this closed line is a diaphragm-controlled valve which is designed to keep a constant pressure drop between both sides of the throttle valve. That is, the inner diaphragm chamber of the diaphragm-controlled valve is directly connected, via this closed line, with one side of the throttle valve, while the other side of the throttle valve is connected with the outer diaphragm chamber of the diaphragm-controlled valve via a closed line starting from a point of the inlet line between the throttle valve and the centrifuge.

If the system of the present invention comprises more than two centrifuges, the above-described arrangement between the centrifuges may recur between the additional successive centrifuges.

The invention is explained more in detail below, reference being made to the accompanying drawings which illustrate examples of the invention applied to a system for refining a fatty oil and to a system for making soap. In the drawings,

Fig. 1 is a diagrammatic view of a system for constant supply of fatty oil to a first separator shown in Fig. 2;

Fig. 2 is a similar view of this first separator and its closed connection to the next separator;

Fig. 3 is a diagrammatic view of a system for making soap, which embodies another form of the invention, and

Fig. 4 is a similar view of still another form of the invention.

In Fig. 1, 1 designates a tank which through a line 2 feeds a positively working pump 3 inserted in the line 2. In operation, the tank 1 should contain enough oil to keep the pump 3 entirely fed. This can be effected manually or automatically, in the latter case by means of a filling device (not shown) which feeds the tank 1 and which, in a conventional manner, is controlled by the oil level in the tank. The arrows in the various figures indicate the flow direction of the oil or other medium. The line 2 also contains a heater 4 for raising the oil to the required temperature, and a mixer 5 in which the oil is mixed with a reagent solution (for instance, water or an aqueous solution of phosphoric or other acid) for degumming.

If the system has no separate degumming step, this reagent solution may be caustic soda or lye, for neutralization of the fatty acids. The water or the aqueous solution is supplied to the mixer 5 through a line 6 by means of a dosage device (not shown) of conventional type which feeds a constant amount per unit of time in spite of varying counterpressure, for instance, a pump of the gear type. From the pressure or outlet side of the pump 3, a line 7 leads back to the suction or inlet side of the pump. In this line 7 is inserted a diaphragm-controlled valve 8, while a shunt line 9 contains a safety valve 10. Oil, which occasionally can be let through the safety valve 10, is thus discharged to the suction or low pressure side of the pump 3. The line 2 also contains a throttle valve 11 which in co-operation with the valve 8 is to ensure constant supply to the subsequent separator.

The valve 8 contains a diaphragm 12 dividing the upper space of the valve into the outer diaphragm chamber 13 and the inner diaphragm chamber 14, while the lower space of the valve is divided by a partition 15 into

an inlet chamber 16 and an outlet chamber 17. In the partition 15 is a valve opening which is throttled by a valve body 18. A spindle 19 supporting the valve body 18 is connected to and controlled by the diaphragm 12, which is adapted to be biased by a constant force, in this case a spring 20 adjustable by means of a screw 21.

A line 22 starting from the line 2 opens into the outer diaphragm chamber 13 of the valve 8, while the line 7 opens into the inlet chamber 16 of the same valve and via the latter chamber is in unthrottled communication with the inner diaphragm chamber 14. Requisite manometers are shown at 23, 24, and 25, and these may be assumed to indicate the pressures 0.2, 3.5, and 3.0 kg./cm.² during normal operation. The amount of oil discharging from the line 2 may be assumed to be 2000 l./h., while the capacity of the pump 3 may be, say, 3000 l./h. Disregarding the liquid supply through the line 6, 2000 l./h. are supplied from the vessel 1, while 1000 l./h. go back through the line 7 to the suction side of the pump 3.

The purpose of the system described above is that a constant pressure drop of, say, 0.5 kg./cm.² is to exist between both sides of the valve 11. At a certain adjustment of this valve, a certain amount of oil is discharged per unit of time from the line 2, independently of the absolute magnitude of each pressure. If now the oil discharging from the line 2 meets an increased counter-pressure, this pressure propagates through the line 22 to the outer diaphragm chamber 13 of the valve 8. This results in the diaphragm 12 being pressed downward so that the valve body 18 will throttle the valve opening in the partition 15. This obstructs the flow through the valve 8, so that a compensating counterpressure is built up in the chambers 16 and 14 and consequently between the pump 3 and the valve 11. The diaphragm 12 is then returned upward until it attains the state of equilibrium again. In this way, a constant pressure drop is always ensured between both sides of the valve 11 and, thus, a constant flow through it. Upon a pressure drop on the suction side of the pump 3, the valve 8 operates in the same manner as described above. The valve 8 will, of course, work in the opposite manner in response to pressure changes of opposite kind.

According to Fig. 2, the line 2 opens into a hermetically closed separator 26 where the oil is freed from gums and is discharged through a line 27 in which there is inserted a valve 28 serving to adjust the boundary level (neutral zone) in the separator 26. The gums leave separator 26 through an outlet (not shown) opening into the open atmosphere. The pressure, for instance 1.5 kg./cm.², of the discharging oil may be read on a manometer 29. In the line 27 are inserted a heater 30, a positively working pump 31 and a mixer 32. Into the latter opens a line 33, through which a reagent such as caustic alkali lye may be supplied by means of a dosage device (not shown) of a kind similar to that which feeds the line 6. A quantity of oil of 2000 l./h. passes from the line 2 into the separator 26 and this oil passes on through the line 27 into another hermetically closed separator 34 which in its oil discharge line 35 has a throttle valve 36. By means of this valve the pressure of the discharging oil may be adjusted to a value suitable for the boundary level in the separator 34, for instance 2.0 kg./cm.², which may be read on a manometer 37. The soapstock separated in the separator 34 is discharged through an outlet (not shown) opening into the open atmosphere. The pump 31 is, like the pump 3, assumed to have a capacity of 3000 l./h., and therefore 1000 l./h. must be forced by the counterpressure in the separator 34 to flow back to the suction side of the pump through a return line 38. The pressure on the pressure side of the pump 31, for instance 3.0 kg./cm.², may be read on a manometer 39. A line 40, with a safety valve 41 inserted in it, is branched off from the line 38. Any oil that possibly may be let out through the line 40 is caught by an outlet funnel 42.

In the line 38 is inserted a diaphragm-controlled valve 43, the parts of which have the same reference numerals as corresponding parts in the valve 8. A manometer 44 is inserted on the suction side of the pump 31, where a constant pressure of for instance 0.2 kg./cm.² is to be maintained.

If the pressure on the suction side of the pump 31 drops below a predetermined value, which may be adjusted by changing the tension of the spring 20 in the valve 43, 10 the valve diaphragm 12 and the valve body 18a move downward. Consequently, an increased quantity of oil enters through the valve opening in the partition 15a of valve 43, until the predetermined pressure on the suction side of the pump is attained again, whereupon the diaphragm resumes its state of equilibrium.

A pressure increase arising, for example, in the separator 34 propagates through the lines 27 and 38 to the inlet chamber 16 of the valve 43, where it acts through the valve opening and the chambers 17 and 14 to move 20 the diaphragm 12 upward. The valve opening is thus throttled by the valve body 18a so that an increased pressure is built up in the chamber 16. In other words, a pressure increase in the separator 34 produces a corresponding pressure increase on the pressure side of the pump 31. After the diaphragm 12 of valve 43 has resumed its state of equilibrium, this causes the feed pressure to the separator 34 to become constant again. At the same time, the first separator 26, being uninfluenced by these pressure variations, discharges against the constant pressure on the suction side of the pump 31 and thus operates without disturbances from other pressure variations arising in the system.

The oil discharging through the line 35 may then be 35 subjected to further treatment required for obtaining a refined product, the arrangement between the separators 26 and 34 recurring between any additional successive separators.

The system shown in Fig. 3 includes a feed line 45 from a saponification step (not shown). The feed line 45 leads into a mixer 46 to which graining electrolyte is supplied through a line 47. The grained soap is supplied by means of a pump 48 to a hermetically closed centrifugal separator 49 in which the neat soap is separated 46 from the spent lye. The neat soap is thereupon discharged through a line 50, which is directly connected hermetically in the usual manner to the rotor of the separator 49, this line 50 containing a valve 51 which keeps constant pressure in the separator outlet proper and which may be a diaphragm-controlled valve of a design 50 similar to the valves 8 and 43 shown in Figs. 1 and 2. A valve 51a of similar construction is also provided in line 50 and serves to keep a constant pressure at the inlet side of valve 51a. In the line 50 is also a gear pump 52 by means of which the neat soap is conveyed 55 to a mixer 53. Fitting electrolyte is led into this mixer through a line 54. The fitted soap goes from the mixer 53 into another hermetically closed separator 55 from which fitted soap discharges through a line 56 having a valve 57 and, if desired, a gear pump or screw pump 60 58. The valve 57 is to keep constant pressure in the outlet from the separator 55 and may be of the same type as the valve 51. The other separated components from the two separators 49 and 55 (spent lye and nigre, 65 respectively) are discharged through lines 59 and 60, respectively, directly connected hermetically to the rotors in the respective separators. The lines 59 and 60 have valves 61 and 62, respectively, and pumps 63 and 64, respectively. The valves 61 and 62 are to keep a constant pressure in the respective separator outlets. The nigre leaving through the line 60 is returned to the mixer 46, where its content of soap is recovered by graining. In each of the outlets from the two centrifuges there is thus maintained a constant counterpressure by means of the 70 valves 51, 57, 61 and 62, whereby the boundary surfaces 75 valves 51, 57, 61 and 62, whereby the boundary surfaces

(neutral zones) between the two components to be separated in the centrifuges maintain their positions independently of the fluctuations that may occur in the quantities flowing through the centrifuges.

The pump 52 is provided with a return line 65 which connects the pressure side of the pump with the suction side of the pump and in this line is inserted a valve 66 which opens only at a determined pressure drop between the pressure and suction sides of the pump.

In the system of Fig. 4, the constant pressure in the line between the centrifuges is maintained primarily on the pressure side of the pump, and the throughflow preferably is kept constant. The centrifuges here are shown

for carbonyl compounds, had been developed with 2,4-dinitro phenyl hydrazine and alcoholic KOH. E is equal to 1 in entirely transparent oil and increases along a logarithmic scale as the degree of transparency is decreased. The two oils were thereupon bleached in vacuum at 120° C. with 2% activated bleaching earth, whereupon peroxide number and carbonyl content were determined for the bleached oils as well as the oxidation stability of these oils. The latter test was effected by blowing through oxygen gas at 40° C., in which test the increase of the peroxide number after a certain time was determined. The results are shown in the following Table I.

Table I

	Analysis of lye-treated, washed and dried oils		Analysis of bleached oils		
	Peroxide number milliequiv./l	Carbonyl content e./g. at 460 m μ	Peroxide number milliequiv./l	Carbonyl content e./g. at 460 m μ	Time in hours for attaining the peroxide number 10
Oil refined in open plant.....	2.5	1.63	0.0	1.94	140
Oil refined in all-hermetic plant.....	0.6	1.41	0.0	1.60	170

at 67 and 68 and the inlet to the first centrifuge is shown at 69. In the line 70 between the two centrifuges is inserted a pump 71 which is shown as a centrifugal (non-positive) pump, although it may be a gear pump with a return line. A valve 72, which may be of the same type as the valve 43 in Fig. 2, is provided to keep constant pressure in the line 70 on the pressure side of the pump 71. In Fig. 4, however, the valve 72 is shown to be actuated by a manometer 73 which, through a suitable operating connection 74, controls an actuator 72a of the diaphragm type for the valve 72 so that the latter throttles the line 70 if the pressure in the inlet to the centrifuge 68 rises, and vice-versa. With the conditions given above, the pressure on the suction side of the pump 71 will be kept constant, and therefore the centrifuge 67 discharges into the line 70 against a constant pressure. In the outlet 75 from the centrifuge 68 is a controllable throttle valve 76.

The effect of the invention as applied to refining of fatty oils is illustrated by the following examples:

EXAMPLE 1

An amount of crude rapeseed oil with a content of free fatty acids of 2.3% and a peroxide number of 0.8 milliequivalent/l. was divided into two parts, of which one was continuously refined in a system containing open separators, where the oil is mixed with air in the inlet of the separators and thereupon is thrown out from the bowl into the open separator covers, where the oil is spread like a mist and comes into very intimate contact with air. The other half was continuously refined in a system comprising hermetically closed separators which were hermetically connected together according to the present invention.

Both the refining plants were equipped with three separators of which the first was used for neutralization, the second for re-refining, and the third for washing. Each of the plants also comprises a drying section operating under vacuum.

The peroxide number for the neutralized, re-refined, washed, and dried oils was determined, stated as milliequivalents per litre, and so was the carbonyl content which, owing to insufficient knowledge of the molecular weight of the carbonyl compounds present in the oil, was calculated as extinction (E) per gram of oil in 50 ml. solvent at 460 m μ (ultra violet light) in 1 cm. cell, after the red hydrazone colour, specific

As appears from the table, the peroxide number and the carbonyl content are both highest for the oil refined in the presence of air. When bleaching, the peroxide number falls to zero, while the carbonyl content increases, evidently owing to carbonyl compounds being formed when the peroxides are split. The peroxide number of the lye-treated oil gives therefore an indication of how much the oil has been damaged owing to presence of oxygen during the lye-refining operation. The comparative test of the stability of the two oils shows further that the time consumed during oxidation for attaining a certain peroxide number is 20% longer for the oil refined in a closed system than that refined in an open system.

EXAMPLE 2

A quantity of rapeseed oil with peroxide number 2.0 milliequivalent/l. was refined in a continuously operating all-hermetic refining system according to the present invention, it being found that the peroxide number for the lye-treated, washed and dried oil was 1.8 milliequivalent/l. Another quantity of the same oil was deaerated in vacuum before refining, and in doing so the oxygen dissolved in the oil was removed almost completely. From the vacuum tank, the deaerated oil was pumped to the all-hermetic system without coming into contact with air. The lye-refined, washed and dried oil had a peroxide number of only 0.4 milliequivalent/l., i.e. considerably lower than for the non-deaerated oil and also lower than for the all-hermetically treated oil mentioned in Example 1, although the peroxide number of crude oil was considerably higher before refining.

EXAMPLE 3

A quantity of soyabean oil with a content of free fatty acids of 0.3% and a peroxide number of 2.3 milliequivalent/l. was refined, in one case, in an open system and, in the other case, in an all-hermetic system, which were both of the same kind as described in Example 1.

The oils were thereupon bleached in vacuum with 2% bleaching earth at 120° C. and deodorized at 230° C. and 5 mm. Hg. The peroxide number was determined for the lye-treated oils as well as for the bleached and deodorized oils and, further, the oxidation stability and carbonyl content of the bleached and deodorized oils were determined. The result of these tests, which appear from the following Table II, show that all-hermetically treated oil is superior in every respect to that treated in

open system (also after bleaching and deodorization) and that the time consumed for obtaining a certain peroxide number when oxidizing the deodorized oils is 30% longer for the all-hermetically treated oil than for the oil treated in open system.

The hermetically closed centrifugal separators used in the new system may be any of the well-known types, such as De Laval "Air-Tight" separators.

Table II

	Analysis of lye-refined oil		Analysis of bleached oil		Analysis of deodorized oil		
	Peroxide number milli-equiv./l	Peroxide number milli-equiv./l	Carbonyl content e.g. at 460 m μ	Time in hours for attaining the peroxide number 10	Peroxide number milli-equiv./l	Carbonyl content e.g. at 460 m μ	Time in hours for attaining the peroxide number 10
Oil refined in open plant	3.1	0.33	2.27	158	0.0	1.76	175
Oil refined in all-hermetic plant	2.3	0.28	1.94	200	0.0	1.45	230

We claim:

1. The combination of two hermetically closed centrifugal separators adapted for continuous operation and adapted to be controlled independently of each other, each separator having an inlet and outlets, an hermetically closed flow line connecting an outlet of the first separator with the inlet of the second separator, whereby the separators are connected in series, pumping means in said closed line having a capacity at least equal to the maximum discharge rate from said outlet of the first separator, an adjustable throttle member in an outlet of the second separator, and a device operatively connected to said closed line for maintaining constant pressure in a part of said line.

2. The combination according to claim 1, in which said device is located to maintain constant pressure in said closed line between the first separator and the pumping means.

3. The combination according to claim 1, in which said pumping means is a non-positive pump.

4. The combination according to claim 1, in which said pumping means is a positive pump having a return line connecting the pressure and suction sides of the pump.

5. The combination according to claim 1, in which the adjustable throttle member is a valve for maintaining constant pressure in said outlet of the second separator.

6. The combination according to claim 1, in which said device is a valve for maintaining constant pressure in said outlet of the first separator.

7. The combination according to claim 1, comprising also valves in the other outlets of the separators for maintaining constant pressure in each of said last outlets.

8. The combination according to claim 1, in which said pumping means is a positive pump having a return line connecting the pressure and suction sides of the pump, the system comprising also a valve located in said return line and operable to open in response to a predetermined pressure difference between the pressure and suction sides of the pump.

9. The combination according to claim 1, in which said pumping means is a positive pump having a return line connecting the pressure and suction sides of the pump, said device being a valve located in said return line and operable to maintain constant pressure on the suction side of the pump.

10. The combination according to claim 1, in which said pumping means is a positive pump having a return line connecting the pressure and suction sides of the pump, said device being a valve located in said return line and operable to maintain constant pressure on the suction side of the pump, the system comprising also an

adjustable valve located in the closed line between said outlet of the first separator and said pump and its return line.

5 11. The combination according to claim 1, in which said pumping means is a positive pump having a return line connecting the pressure and suction sides of the pump, said device being a valve located in said return line and operable to maintain constant pressure on the suction

side of the pump, the system comprising also means connected to the inlet of the first separator for supplying feed thereto at a constant rate.

25 12. The combination according to claim 1, in which said pumping means is a positive pump having a return line connecting the pressure and suction sides of the pump, said device being a valve located in said return line and operable to maintain constant pressure on the suction side of the pump, the system comprising also means connected to the inlet of the first separator for supplying feed thereto at a constant rate, said last means including a closed feed line to said last inlet, a positive feed pump in said feed line, an adjustable throttle valve in said feed line between said feed pump and the first separator, a closed return line connecting the pressure and suction sides of said feed pump, said last return line leading from the feed line at a point between the feed pump and said 30 throttle valve, a control valve located in said last return line and having a valve body and a diaphragm operatively connected to said valve body, the diaphragm partly defining chambers at opposite sides of the diaphragm, one of said chambers being connected through the last return line to the inlet side of said throttle valve, and a pipe line connecting the other chamber to the feed line at the outlet side of said throttle valve, whereby said control 35 valve maintains a constant pressure drop across the inlet and outlet sides of said throttle valve.
